UNITED STATES PATENT OFFICE.

HERMAN A. MUELLER, OF CLEVELAND, OHIO.

BREAD BOX.

Application filed March 31, 1921, Serial No. 457,276. Renewed January 31, 1925.

To all whom it may concern:

Be it known that I, HERMAN A. MUELLER, a citizen of the United States, and resident of Cleveland, in the county of Cuyahoga and State of Ohio, have invented certain new and useful Improvements in Bread Boxes, of which I hereby declare the following to be a full, clear, and exact description, such as will enable others skilled in the art to which it appertains to make and use the same.

The objects of the invention are, to provide an improved box for containing bread, cake and pies or other baked articles, which is provided with separate compartments for the different articles, and in which a common door is employed for closing the one opening leading to all compartments; this door when opened gives access to all the articles in the box.

It is also provided with ventilating openings which prevent mold from forming upon the baked articles, but which are not large enough or so placed as to permit complete drying out of the moisture in the baked articles.

This invention includes a box provided with a front opening and with a shelf or shelves forming compartments separated from each other thereby, and a door provided with marginal flanges which swing freely upon pivoted bolts or pins upon each side of the horizontal central partition, the aforesaid bolts passing also through the sides of the box.

This partition and the flanged door are removable together from the box, to permit cleaning all the parts.

The invention is herewith more fully described, illustrated in the accompanying drawings, and specifically pointed out in the claims.

In the accompanying drawings Fig. 1, is a front elevation of the box showing the door closed; Fig. 2, is a vertical central longitudinal section thereof; Fig. 3, is a perspective of the box with the cover opened; Fig. 4 is a perspective of the door.

In these views A, is a box, provided with a large opening B, in the front wall thereof, C and D are upper and lower flanges at the front of the box, E, is a horizontal partition having depending rear and side flanges F, and G, G, respectively.

This partition is positioned intermediate of the top and bottom wall of the box, and is

bolted at H, to the rear wall thereof; I, is the door, which is provided with the flanges J, J, on each side thereof.

These flanges are pivoted to the flanges G, G, of the partition, by means of the bolts K, K, which pass also through the side walls of the box.

The partition is also supported upon the bolts K, K, and the flanges J, J, of the door pass between flanges G, G, and the side walls of the box.

The door can be swung to a substantially vertical position, the top edge of the door making contact with the flange C, upon the front of the box and the bottom edge of the door resting upon the inwardly turned edge L, of the lower flange D, of the front of the box.

The door swings freely around the front edge of the aforesaid partition and when thrown back assumes a substantially horizontal position above the articles, which rest upon the partition, also the lower partition of the box will be open for access to its contents.

A knob M, is employed for raising and lowering the door.

The side edges of the door fit closely against the sides of the box, and when closed there will be no opening through which insects can enter the box.

Small perforations N, N, in the sides of the box above and below said partition permit sufficient air to prevent mold from forming upon the baked articles in the box, but are not large enough to cause them to become dry.

Having described the invention what I claim as new and desire to secure by Letters Patent is:

1. In a bread box, an enclosure provided with a vertical front opening, a horizontal partition attached to the rear wall of said enclosure, and a flat swinging door for said opening, said door provided with marginal opposite flanges, said flanges pivoted to the sides of said partition, and to the sides of said enclosure, said door revolvable within said enclosure and adapted to assure a vertical position to fill said front opening, when swung forwardly and to assume a horizontal position in said box when swung rearwardly.

2. In a bread box, an enclosure provided with a vertical front opening, said box provided with flanges above and below said

- opening, a door revolvable in said box, hinge members for said door, a horizontal partition in said enclosure, said partition having flanged sides, pivots passing through said flanged sides of said partitions and through the side walls of said box, said hinge members upon said door revolvable on said pivots between the sides of said partition and the side walls of said box, the upper and lower edges of said door turned reversely and adapted to rest upon the said upper and lower flanges above and below said vertical front opening in said box, when said door is closed, said door assuming a horizontal position in said box when withdrawn therefrom.

3. In a bread box, an enclosure provided

with a vertical front opening, said box provided with flanges above and below said opening, a door revolvable in said box, hinge members for said door, a horizontal partition in said enclosure, said partition having flanged sides, pivots passing through said flanged sides of said partition and through the side walls of said box, the upper and lower edges of said door resting upon the said upper and lower flanges above and below said front opening in said box, when said door is closed, and ventilating openings in the sides of said box, above and below said partition.

In testimony whereof, I hereunto set my hand this 25th day of February, 1921.

HERMAN A. MUELLER.
